Inventor:

Hugh Hughes

United States Patent Office.

HUGH HUGHES, OF UTICA, NEW YORK.

Letters Patent No. 66,843, dated July 16, 1867.

IMPROVEMENT IN DOOR-SPRINGS.

The Schedule referred to in these Letters Patent and making part of the same.

TO ALL WHOM IT MAY CONCERN:

Be it known that I, HUGH HUGHES, of the city of Utica, in the county of Oneida, and State of New York, have invented a new and useful Door-Spring for closing doors; and I do hereby declare that the following is a full, clear, and exact description of the construction and operation of the same, reference being had to the annexed drawings, and to the letters of reference marked thereon, making a part of this specification.

The nature of my invention consists in the adoption of a thong or strap of India rubber or other elastic material, which is so connected with a peculiar mechanical arrangement of connected parts as to form a cheap, simple, and useful spring for the purpose aforesaid.

Figure 1 of the annexed drawings exhibits a model door with my spring attached.

The spring, including its construction, consists of three parts: *a* is the frame or stationary part, and is screwed to the door-frame *J*, *b c* is the arm that actuates the spring, and *d* is the elastic spring, and connects the other two parts. The stationary frame *a* has two horizontal studs, *e* and *f*, the former being short, and the latter being a little more extended. The former has one or more vertical pins, over one of which the rear end of the rubber spring *d* is looped, as seen at *g*. More than one pin may be used here as alternatives to adjust the tension of the spring. The stud *f* has also a vertical pin, not for the rubber spring, but for the hinge or fulcrum of the actuating arm *b c*, as seen at *C*. The arm *b c* not only has the eye at *C* forming with the last-mentioned pin the hinge of the article, but it has another vertical pin *h*, and over this latter pin is looped the other end of the rubber spring *d*. Between the hinge *C* and the last-mentioned pin the arm *b c* curves backward, as shown, and widens out upward, forming a semicircular curve or cam. The rubber spring is looped at one end over the pin at *g*, and being stretched around the cam aforesaid, the other end is looped over the pin at *h*, and with such tension that the extremity of the arm *b c* is pressed against the plane of the door through the intervention of the sheave *n*. This sheave is made to turn loosely on the pendent pin *l*, and rolls upon the surface of the door as it opens and closes, with a constant tendency, through the action of the spring *b c*, to close the door. This is all clearly seen by an inspection of the drawing.

Figure 2 exhibits a top view of the article described. *J* is the door-casing, *a* the edge of the stationary plate screwed to the casing, *d* is the rubber spring, and *b c* the actuating arms.

Figure 3 is a like top view, with the door *m* partly open—

All the parts being designated by corresponding letters of reference in all the drawings.

Having thus described my invention and its construction and operation, what I claim as my invention, and desire to secure by Letters Patent, is—

The construction and arrangement of the door-spring above set forth and described.

HUGH HUGHES.
